UNITED STATES PATENT OFFICE.

GEORGE D. WHITE, OF PORT ARTHUR, TEXAS, ASSIGNOR TO THE TEXAS COMPANY, OF NEW YORK, N. Y., A CORPORATION OF TEXAS.

APPARATUS FOR HEATING STILLS.

Application filed April 5, 1923. Serial No. 630,001.

This invention relates generally to improvements in heating apparatus for stills in which hydrocarbon oils are distilled and has particular reference to the provision of 5 suitable heating means for stills in which is carried on the decomposition or cracking of oil.

In the cracking of hydrocarbon oils difficulty has been experienced in applying to 10 the stills the heat required to carry on the cracking operation because the decomposition is attended with a formation of comparatively large quantities of carbon or coke which readily becomes attached to heated 15 metal walls, and since with the heating apparatus which has been commonly employed for heating stills it has been necessary to carry furnace temperatures considerably in excess of the temperature desired in the stills 20 in order to maintain such temperature therein. The application of this heat to the carbon coated metallic surfaces produces "red spots" with the resultant deterioration and distortion of the metal and the breaking 25 down of the stills. When the stills are operating under high pressure not only is the length of a run cut down in this manner but the operation is attended with great hazard. Moreover in the various types of liquid fuel 30 burning furnaces which have hitherto been used a considerable draft is ordinarily required in the furnace to maintain the stills at the cracking temperature and it has been impossible to avoid localized overheating of 35 those portions of the stills in the more direct path of the draft. Moreover the great draft used necessitates the use of an excessive amount of fuel.

Some of the objects of my invention are, 40 therefore, to provide means for reducing the temperature differential between the furnace and the still, to reduce the amount of draft required and to provide heating means by which an even heat is applied to the still 45 and in which localized overheating is largely avoided.

Another object is to provide means for accurately regulating and controlling the 50 temperature in various parts of the furnace so as to obtain thereby a more accurate control of the cracking operation in the stills. In the ordinary type of oil or coal fired furnaces, which are commonly used for cracking stills, it is not possible to obtain that

regulation of the temperature in the furnace 55 which is necessary to carry on the cracking operation to the best advantage.

A further object is to provide means for rapidly cooling the stills at the completion 60 of a run.

Other objects as well as various advantages of the invention will become apparent in the following detailed description thereof reference being had to the accompanying drawings 65 wherein:

Figure 1 is a longitudinal section of an apparatus constructed in accordance with the invention and constituting an embodiment thereof.

Figure 2 is a sectional view taken on the 70 line 2—2 of Figure 1.

Figure 3 is an end elevation.

Figure 4 is a sectional plan view taken on the line 4—4 of Figure 1.

Figure 5 is a multi-sectional plan view 75 taken on the lines 5—5 of Figure 1.

Figure 6 is a detailed sectional view illustrating a preferred manner of mounting the burners in the furnace.

The invention has reference to apparatus 80 for heating stills, converters and the like, either of the horizontal or vertical type. As the invention, however, provides especially advantageous heating equipment for vertical stills, it is illustrated and described in detail herein as thus applied. In the particular example of the invention illustrated it is shown as employed with a plurality or battery of stills or converters; it is to be understood, however, that the invention contemplates 85 heating apparatus for stills arranged singly or in multiple. In the embodiment of the invention thus illustrated then the invention is shown as applied to a plurality of vertical stills 10. Each still is adapted to 90 be heated in its intermediate portion, and is arranged with a comparatively cool portion at the bottom for the purposes of carbon and residuum collection and removal and with a vapor space above the furnace. As 95 shown, the stills may be interconnected by means of vapor equalizing lines 11 and liquid level lines 12.

The stills are mounted in a furnace which includes a refractory or fire brick wall 13 105 which, as shown, is arranged about the stills in substantially oval or elliptical form. While the furnace may be constructed in the

form of a rectangle or square I prefer to construct it with a rounded inner surface in order to avoid the formation of pockets or dead spaces, and consequently the inner contour of the furnace preferably assumes more or less the form of a circle when a single still is employed and an ellipse when a plurality of stills are used.

Exteriorly of the fire brick wall 13 is a wall 14 composed of diatomaceous earth, asbestos, or magnesium slabs or other suitable insulating material. Bulk asbestos may be used, if desired, being packed in between walls of the furnace; for obvious advantages in construction, however, it is preferable to use slabs. The furnace includes an exterior wall preferably in the form of a metallic casing, such as a steel casing 15. By constructing the furnace with an outer steel wall, an inner refractory wall and an intermediate insulating wall it is possible to substantially prevent loss of heat by radiation while at the same time avoiding the thick and heavy furnace constructions commonly employed.

The furnace is shown as being supported on pillars or concrete blocks 16 so that the stills may be supported above the ground surface in order that access may be had to the bottom of the stills for cleaning purposes and the like. As shown in the drawing the bottom of the furnace may comprise a fire brick floor 17, an exterior concrete floor 18 and an intermediate layer of sand 19. The furnace is provided with a closure at the top which preferably assumes the form of a suspended tile arch 20. The means for supporting the still in the furnace is positioned outside of the furnace. Thus each still may be equipped with a plurality of lugs 21 which are adapted to rest on I beams 22 arranged above the tile arch 20.

The furnace is provided with a plurality of openings or conduits 23 which extend through the wall of the furnace. The outer end of each conduit is inclined as shown in the drawings and a hinged door 24 is adapted to form a closure over the outlet. The weight of the door is sufficient to normally retain the gases within the furnace but in case of an explosion the door will swing on its hinge so as to open and relieve the pressure in the furnace. Two rows of conduits 23 are preferably provided one row being near the top of the furnace and the other row near the bottom. At the conclusion of a run the doors 24 may be opened and the ensuing circulation through the furnace and about the stills 10 effects a rapid cooling of the furnace and stills. It will be observed that the stills are spaced from the furnace walls so that the air entering the conduits 23 may readily come in contact with the exterior still surfaces. In practice this ar-

rangement greatly reduces the time required for cooling the stills at the end of a run.

Gas or fuel for the furnace is supplied from a suitable source by means of the pipe 25 which, as illustrated, terminates in branch lines 26^a and 26^b each of which extends along one side of the furnace. Each line 26^a and 26^b constitutes a header from which extends a plurality of vertically extending pipes 27 provided with horizontal connections 28 each of which terminates in a burner 29. The pipe 25 is equipped with a valve 30, and each connecting line 28 has a valve 31 so that each burner may be regulated and controlled independently of the others. As clearly shown in Figure 6, each burner extends through a hole 32 in the furnace wall. Into each opening 32 is closely fitted a pipe or sleeve 33 and asbestos or other suitable packing or insulating material 34 is inserted within the sleeve so as to form a tight joint about the burner 29. Adjacent each burner is a small opening through the furnace wall into which is inserted a pipe 35 provided with a removable cap or closure 36. The pipe 35 serves as a means for introducing a torch inside the furnace for the purpose of lighting the gas burner 29.

The vertical pipes 27 are positioned at points preferably between the several stills 95 and the burners are arranged at such angles as to direct the flames into the spaces intermediate the stills. In this way the flames do not impinge directly on the surfaces of the stills. The result is that localized overheating is avoided and a substantially even heat is applied to the still surfaces.

By means of the several valves in the gas lines the quantity and degree of heat from each individual burner may be accurately regulated with the result that temperature conditions in the furnace may be controlled with a high degree of precision. Thus the several stills may be readily held at the same temperatures or at different temperatures, as may be desired. Moreover, the heat applied to each individual still may be so regulated as to maintain the same or different temperatures in different portions of the still under the varying conditions of operation which may be encountered. Thus, for example, it may be desired to introduce the oil being treated, or to return reflux condensate, to a given portion of the still, in which cases a higher temperature may be applied with safety to that portion of the still receiving the fresh oil and, in fact, it is ordinarily desirable to apply a higher temperature or a greater amount of heat to that portion of the still which receives the charge or the reflux, and in case of a battery of stills to apply more heat to the still receiving the fresh oil than to the other stills.

It has been found that in the liquid phase

cracking of hydrocarbons the time factor is an important element to be considered and that, for example, a successful commercial operation may be carried on in which 5 higher boiling oils are converted into lower boiling products by being maintained at a temperature, at which an efficient rate of decomposition occurs, for a time sufficient to cause a substantial conversion, in this way 10 avoiding the relatively high vapor phase cracking temperatures which have sometimes been employed. The oil to be thus treated may be passed successively through a plurality of stills, as 10, arranged to be heated 15 in the manner described herein. The oil attains successively advanced stages of decomposition in its passage from one still to another and the furnace temperatures about each still respectively, may readily be controlled to meet this condition and maintain 20 the desired cracking temperature in the stills.

It is apparent that the furnace temperatures required about the several stills or 25 reaction chambers will vary with conditions of operation, such as, what particular stills, if any, receive reflux or oil of a temperature lower than the desired cracking temperature, whether the oil charge enters the stills at or 30 above the desired cracking temperature or at a lower temperature, whether the charge is introduced into one still and is passed to the others in succession or whether the charge is split among a plurality of the stills, and 35 other variable factors as will be understood by those skilled in the art. Whatever the conditions of operation may be, however, by means of my invention the several converters may be maintained at the desired 40 temperatures.

If desired the furnace may be equipped with a ring burner 37 positioned near the bottom of the furnace. I have found, however, that ordinarily the ring burner is unnecessary and that it is generally more 45 advantageous to use merely the horizontal burners disposed at various elevations as has been described herein.

The furnace gases are drawn off from the 50 furnace chamber through a plurality of openings 38 positioned near the top of the furnace. These openings lead to a gas conduit 39 arranged about the furnace and terminating in an outlet pipe or flue 40 which is provided with a damper 44. When operating conditions have been established the damper may be choked in order to hold the 55 hot gases in the furnace chamber. In this manner the desired temperatures in the stills can be maintained with a minimum of fuel, since an excessive draft through the furnace chamber is avoided and the gases are retained in the furnace for a time sufficient to insure a maximum transfer of heat to the 60 stills. If desired the gases may be removed 65

from the furnace chamber through one or more openings at either one of the sides or ends of the furnace. It is generally preferable, however, to provide a plurality of openings extending about the entire furnace, such as is illustrated in the drawings. 70

The furnace may be equipped with a number of peep holes 41 and with such thermometers, pyrometers and the like as may be deemed necessary or desirable. As clearly 75 shown in Figure 3 stairways 42 and platforms 43 are provided in order that the attendants may have ready access to the doors 24, the burners, peep holes and the like.

The use of the apparatus of my invention 80 effects a substantial reduction of the temperature differential between still and furnace which is highly desirable, since the lower the temperature applied to the exterior still surface the less the tendency to bake 85 carbon deposits on the interior still walls. In order to indicate the superior advantage gained in employing my heating apparatus it may be stated that in some cases the invention has been applied in carrying on the 90 cracking of petroleum hydrocarbons in a series of stills maintained at temperatures around 700° F. to 800° F. To hold this temperature in the stills, under the different 95 operating conditions employed, furnace temperatures from around 800° F. to 1200° F. were used. When using the old types of heating equipment furnace temperatures of 1600° F. and even higher had been necessary to maintain the cracking temperatures indicated under the same operating conditions. 100

Apparatus of preferred form and construction has been illustrated and described for the purpose of showing a way in which this invention may be used but the inventive 105 thought upon which the application is based is broader than the illustrative embodiment thereof and I therefore intend no limitations other than those imposed by the appended 110 claims.

What I claim is:

1. Apparatus for cracking hydrocarbon oils comprising a battery of spaced vertical stills, a furnace chamber disposed about said stills the walls of which chamber are spaced from the stills, a plurality of gas burners extending through opposite walls of said furnace and spaced from each other horizontally and vertically at points intermediate the several stills, the arrangement being such that heat is applied at a plurality of distributed points within the furnace in such a manner as to avoid direct contact of the flames against the still walls whereby hot spots are prevented, and a plurality of flue passages spaced from each other in the upper part of the furnace whereby the furnace gases are caused to travel upwardly through the furnace and are withdrawn at distributed points in the upper part thereof. 115 120 125 130

2. In furnace apparatus for cracking stills, the combination with a battery of vertical stills, of a furnace chamber within which the stills are mounted, a plurality of gas burners distributed throughout said chamber, a plurality of outlets in the upper part of said chamber adapted for removing com-

bustion gases and a plurality of openings in the furnace wall establishing communication between the furnace chamber and the outside atmosphere and doors for said openings. ¹⁰

In witness whereof I have hereunto set my hand this 21st day of March, 1923.

GEORGE D. WHITE.
